LEAD SHARPENER

Michael Georges, Norwood, Mass.

Application June 24, 1953, Serial No. 363,726

16 Claims. (Cl. 120—96)

This invention relates to means for sharpening the leads of pencils and is particularly concerned with the sharpening of the leads now used in so-called lead holders or refill drawing pencils.

As is well known, hand driven and motor driven pencil sharpeners are old in the art. At the present time, the most commonly used pencil sharpeners for sharpening wood encased leads are hand driven and such sharpeners are satisfactory for the ordinary purposes to which wood pencils are put.

In recent years mechanical pencils have been developed in which the holder is of permanent character having means therein for causing the lead to be progressively moved outwardly from the holder as the lead is used. Such mechanical pencils include those utilizing large diameter leads which are generally used by draftsmen, the approximate dimensions of the commonly used sizes being .078" diameter by 5 1/8" in length. The leads of mechanical pencils cannot be sharpened by that type of sharpener used in sharpening ordinary lead pencils having the wood encased leads.

In drafting and stenographic work, fine lines are used and accordingly it will be understood that the lead must be repeatedly sharpened. Not only must the lead be sharpened, but it must be wiped after each sharpening in order to insure that no carbon particles fall on the drawing or drawing equipment to cause smudges.

Due to the difficulty of sharpening a long unsupported lead point by mechanical means, the customary practice today still involves the use of sandpaper lead pointers or metal files, both of which leave weakening ridges in the lead. Also in limited use is a small hand sharpener into which the lead point is inserted, the hand sharpener being rotated back and forth until a point has been produced. The sharpener just described utilizes sharpening blades which converge to a point and correspondingly when a lead has been sharpened by this means, the end of the lead will be literally pointed, but such point is insufficient in structural strength to stand any use by the draftsman. That is, as soon as the draftsman attempts to utilize a lead sharpened to this extent, the fine point will break off under normal use leaving a somewhat enlarged rough point which when smoothed up slightly, may then be put to satisfactory use by the draftsman.

The use of the hand sharpener is slow, and the subsequent breaking off of the fine point produced thereby is troublesome when it occurs on the drawing and accordingly it is the practice among draftsmen after sharpening the lead according to the best known methods available, to purposely break off the small weak portion of the point before putting the pencil to use. In addition, sharpening by any of these methods requires wiping of the lead.

2

With the foregoing disadvantages of existing practices in mind, it is an object of this invention to provide a lead sharpener which will produce quickly a finished, longer lasting, ready to use point on the lead of a mechanical pencil without the utilization of any judgment or skill by the operator.

It is a further object of this invention to provide a pencil sharpener capable of functioning in such manner that the end of the sharpened portion of the lead will not 10 terminate in a point but rather at a section of small diameter and preferably slightly rounded and capable of producing a satisfactory line and of sufficient structural strength to avoid breakage when initially used.

Another object of the invention is to provide a pencil sharpener so designed that after the sharpening has 15 been completed, further unnecessary grinding away of the lead will be prevented. That is to say, once the lead has been sharpened to the maximum extent, sharpening will cease and cannot be resumed until the end of the lead has 20 been worn or broken away.

Another object of the invention is to provide means 25 automatically operable as the sharpening proceeds to throw the removed carbon particles away from the point into a dust collecting unit so that when the sharpened lead point is removed from the sharpener, it will be free of carbon dust particles to such extent that it may be used without being wiped, and without fear of smudges developing on the drawing from unremoved carbon particles.

Another object of the invention is the provision of a 30 cutting head of small moment of inertia permitting greater usable cutting torque, the use of a smaller motor and more rapid getting up to speed.

Still another object of the invention is to provide electrically operated means for driving the lead sharpener 35 which may be readily switched on and off when the device is to be used and which at the same time will be freely portable so that the collected dust particles may be emptied therefrom periodically.

These and other objects of the invention will become 40 more apparent as the description proceeds with the aid of the accompanying drawings in which,

Fig. 1 is a plan view of the complete unit.

Fig. 2 is a front elevation of Fig. 1.

Fig. 3 is a section drawn to enlarged scale taken on 45 the line 3—3 of Fig. 1.

Fig. 4 is a section on the line 4—4 of Fig. 5.

Fig. 5 is a vertical section of the cutter unit drawn to enlarged scale and taken substantially on the line 5—5 of Fig. 4.

Fig. 6 is a horizontal section taken on the line 6—6 of Fig. 5.

Fig. 7 is a section taken on the line 7—7 of Fig. 8.

Fig. 8 is a vertical section of a cutter drawn to enlarged scale showing a modified construction and taken substantially on the line 8—8 of Fig. 7.

Fig. 9 is a horizontal section taken on the line 9—9 of Fig. 8.

Fig. 10 is a vertical section of the base of the cutting blades mounted in a modified type of blade holder.

Fig. 11 is a horizontal section on the line 11—11 of Fig. 10.

Fig. 12 is a perspective view drawn to reduced scale showing one form of convenient means for securing the complete unit shown in Figs. 1, 2 and 3 on a draftsman's table or other surface.

Referring first to Figs. 1, 2 and 3, the complete motor driven lead sharpener and cleaner comprises a box-like

metal housing 2 which includes a top cover plate 4 to which is affixed a lead dust receptacle 6 secured by the screws 8 passing through the horizontally extending ears 10, the vertical portions 12 of which are glued or otherwise secured to the receptacle 6.

Mounted within the housing 2 is an electric motor 14 preferably of the phonograph type. This motor is low in cost, readily available and runs at a speed suitable to drive the lead sharpener at the correct R. P. M. Motor 14 is affixed to a plate 4. Another plate 16, carrying electrical connections is secured by the bolts 18 to one end of housing 2. An external electrical connection 20 brings the necessary electric current to the motor connections on plate 16. The motor includes a lower shaft bearing 22 and an upper bearing 24.

The motor shaft 26 extends upwardly from the motor through a felt pad seal 28 into the lead powder receptacle 6. On the upper end of shaft 26 is mounted the cutting head 30. The construction of this cutting head will be described in more detail hereinafter.

Actuation of the motor 14 is controlled by a conventional electric switch 32. Rubber feet 34 secured to the bottom of the casing 2 serve to cushion and anchor the unit in conventional manner.

The cutting head 30 which is mounted on the upper end of shaft 26 will now be described. Referring first to Figs. 4, 5 and 6, it will be seen that there is a blade retainer 36 threaded axially at 38 and screwed on the threaded end 40 of shaft 26. A lock nut 41 shown in Fig. 3 may be used if desired. The cylindrical portion of retainer 36 terminates at 42 and thereabove consists of four pie shaped segments 44, 46, 48 and 50. Inserted between these segments are four identical cutting blades 52, 54, 56 and 58 preferably made of hard tool steel. As can be seen in Fig. 6, the interior vertical surfaces of the lower portions of these blades terminate in surfaces at right angles to each other which enables the four blades to fit closely together as shown.

By reference to Figs. 4 and 5 further details of the construction of the cutting blades will be better understood. The view shown in Fig. 5 is taken substantially along the line 5-5 of Fig. 4 with blade 56 removed in its entirety. As all of the blades are identical a description of one will suffice for all. Referring particularly to blade 58 shown in Figs. 4 and 5, it will be seen that there is a horizontal shelf 60 with its exterior edge at right angles from which extends upwardly the cutting edge 62 bounded by the sides 64 and 66. The included angle between the blade faces 64 and 66 is preferably between 60° and 70° as it has been found that this gives a satisfactory scraping action on the lead. The other cutting edges on the other blades are designated as follows: Blade 52 has edge 68, blade 54 has edge 70 and blade 56 has edge 72. The shelf 60 of blade 58 has its counter parts at 74 in blade 52, at 76 in blade 54, and at 78 in blade 56. These four shelves come together to form a horizontal surface which is a plane in which the lower ends of the cutting edges 62, 68, 70 and 72 terminate. As can be seen in Figs. 4 and 5, the cutting edges do not come to a point, but rather terminate in the plane of the shelves to leave a space 80 which constitutes the minimum diameter to which the end of the lead may be sharpened.

Those portions of the blades that are above the tops of the pie shaped segments 44, 46, 48 and 50, which tops are indicated at 82, are spaced apart at 90° so that any lead removed in the sharpening can be thrown out radially to be collected in the lead powder receptacle 6. By varying the dimension 80, which is the distance between the lower ends of each pair of opposed edges of the cutting blades, the minimum diameter of the ends of the lead may be controlled. The included angle between the cutting edges 62 and 70 and between 68 and 72 is preferably between 10° and 20°. By varying this angle as desired through the use of other sets of cutters, the conical formation of the point may be changed from somewhat blunt to a long taper.

Secured to the top ends of the four cutting blades is a lead guide 84. This consists of a circular body portion 86 having a hemispherical depression 88 and a central lead receiving aperture 90. Extending downwardly from the under side of the lead guide are four pie shaped feet shown in Fig. 4 at 92, 94, 96 and 98 which sections fit between the upper ends of blades 52, 54, 56 and 58. The lead guide may be secured in position by cementing the feet to the blades, or brazing the parts together.

It will be understood that all of the parts thus described are assembled in concentric fashion with the center line of shaft 26 coinciding with the center line of blade retainer 36, the center line forming the junction of the four blades and the center line of opening 90 of the lead guide. The parts are also dynamically balanced so that upon rotation of shaft 26, the entire cutting head will rotate smoothly along the axis of shaft 26 as extended.

From the description given thus far, it is believed that the operation of the unit may now be clearly understood.

20 The user starts the cutting head 30 rotating by pressing the switch 32 of the motor putting the latter in operation. Enough of the lead of the mechanical pencil to be sharpened is exposed so that the body of the pencil will not come into engagement with the lead guide. The lead is 25 then inserted downwardly through hole 90, this hole being large enough to take the largest of the conventional sized leads. As the lead moves downwardly, the end comes into engagement with the rotating cutting edges of the blades which assists the lead guide in directing the 30 lead to a vertical position so that it will be truly centered with respect to the rotating cutter. The lead particles as fast as they are shaved from the surface to the lead are thrown radially outward away from the cutting blades to be collected in the bottom of the lead powder receptacle 35 6. As the cutting away of the lead proceeds, the lead moves downwardly within the confines of the four rotating cutting edges, 62, 68, 70 and 72 until the end of the lead engages the bottom formed by the horizontal shelf surfaces at the lower ends of the cutting edges. Further 40 downward movement of the lead is thus prevented and the point at this time is in complete sharpened condition. It is then removed upwardly and withdrawn from the lead guide. The motor may then be shut off to stop the rotation of the cutting head and the operation is complete.

Upon examination of the point produced by this mechanism, it will be seen that the end is circular and not pointed. The diameter of the circular end is equal to the distance 80 which in a preferred form has been found to be approximately .016 inch. This dimension is small enough to give a sharp line suitable for drafting purposes, 50 and at the same time, the lead is strong enough to withstand breakage under the pressures that would normally be applied. Furthermore, an examination of the surface of the lead point will show that it is substantially completely free of all loose carbon particles, and therefore, does not need to be wiped prior to use. That is to say, the point produced by this device is ready for immediate use and accordingly in the course of a day, a substantial amount of time is saved by the user in the sharpening of leads.

60 A modified form of cutter head is shown in Figs. 7, 8 and 9. The difference over Figs. 4, 5 and 6 resides principally in the blade construction. The edges of the abutting lower vertical portions of the blades which in this modification are numbered 100, 102, 104 and 106 are ground away to present flat surfaces 108, 110, 112 and 114. Thus, when the blades are assembled, there is a square vertical hole at the juncture of the four blades. In this hole is placed and secured a wire 116 with its upper end preferably located at the lower ends of the cutting edges of the blade. A hole 118, concentric with the center line of the blades, is provided in the upper end of blade holder 120 which will permit insertion of the wire to proper position. The pie shaped segments that support the lower ends of the blades and which are numbered 122, 124, 126 and 128 act in the same manner

as segments 44, 46, 48 and 50 of Figs. 5 and 6. The cutting head 30 of Figs. 7, 8 and 9 operates in the same manner as that explained above in connection with Figs. 4, 5 and 6.

A slightly different type of blade retainer is shown in Figs. 10 and 11. In this form the blade retainer 130 is formed with a cylindrical opening 132 in its top end. Into this opening the four blades 134, 136, 138 and 140 are inserted as shown in Fig. 11, making a forced fit therein. The inner right angled surfaces of the blades abut and with the help of the retainer wall are held in correct aligned position. These blades may be the same as those disclosed in Figs. 4, 5 and 6, but, as shown, are the same as in Figs. 7, 8 and 9 and accordingly a wire 142 fills the central opening and provides the surface which the lead engages after it has been sharpened to the maximum extent.

Fig. 12 illustrates a simple way of mounting the sharpener on a desk. A bracket 144 has screw holes 146 permitting the face 148 to be screwed to the table. The other face 150 has four headed projections 152 adapted to hold vertically the wall 154 of the housing 2 by means of the inverted key hole openings 156. See Fig. 2. In this way the entire unit may be removed and inverted to dump the collected lead dust from the lead powder receptacle 6.

It will be understood, of course, that the receptacle 6 could be made removable from the casing 2 so that it would not be necessary to disturb the motor and cutting head when emptying the receptacle. However, in my preferred form, I have found it more convenient to have the receptacle integral with the casing as it is thereby possible to have a more secure, rigid unit which is not inconvenient to lift in its entirety and turn up-side-down to empty the lead powder receptacle.

It is my intention to cover all changes and modifications of the example of the invention herein chosen for purposes of the disclosure which do not constitute departures from the spirit and scope of the invention.

I claim:

1. A lead sharpener comprising a rotatable cutting head including in combination a blade retainer, a plurality of radially arranged cutting blades mounted on said retainer, said blades being spaced from each other to provide egress therebetween of shavings removed by said blades, the cutting edges of said blades converging and defining a pyramidal space therebetween to receive the lead of a pencil, the lower ends of said cutting edges terminating in spaced apart relation, a lead guide affixed to the upper ends of said blades, said lead guide having an opening therein concentric with said blades and a substantial depression in its upper surface with sides sloping toward said opening whereby the lead of a pencil can be introduced into said pyramidal space, and means for preventing the downward movement of a lead being sharpened below the lower ends of the edges of said blades.

2. A lead sharpener as set forth in claim 1, said means for preventing the downward movement of the lead that is being sharpened, comprising a wire concentrically aligned with said blades.

3. A lead sharpener as set forth in claim 1, the cutting edge of each blade terminating at its lower end adjacent a horizontal shelf that is integral with said blade.

4. A lead sharpener as set forth in claim 1, the lower inner vertical portions of said cutting blades below said cutting edges having engaging faces, the sum of the included angles between the said faces of all of the blades equaling 360°.

5. A lead sharpener as set forth in claim 1 and comprising in addition an electric motor, a vertical shaft driven by said motor, said rotatable cutting head mounted on said shaft, a lead powder receptacle above said motor surrounding said cutting head and part of said shaft and means for preventing lead powder that may be in said lead

powder receptacle from reaching the bearings of said shaft.

6. A lead sharpener as set forth in claim 1 in which the diameter of the opening of said lead guide is not greater than the diameter of the generated circumference of the upper ends of said blades.

7. A lead sharpener comprising a rotatable cutting head including in combination a blade supporting member, a plurality of radially arranged blades of which at least one has a cutting edge mounted on said member, said blades being spaced from each other to provide egress therebetween of shavings removed by said blade, the said blades converging and defining a pyramidal space therebetween to receive the lead of a pencil, the lower ends of said blades terminating in spaced apart relation, a lead guide above the cutting edges of said blades, said lead guide having an opening therein concentric with said blades whereby the lead of a pencil can be introduced into said pyramidal space, and a stop for terminating downward movement of said lead at a predetermined level.

8. A lead sharpener as set forth in claim 7, said stop comprising a wire concentrically aligned with said blades.

9. A lead sharpener as set forth in claim 7 and comprising in addition an electric motor, a vertical shaft driven by said motor, said rotatable cutting head mounted on said shaft, a lead powder receptacle above said motor surrounding said cutting head and part of said shaft, and means for preventing lead powder that may be in said lead powder receptacle from reaching the bearings of said shaft.

10. A lead sharpener as set forth in claim 7 in which the diameter of the opening of said lead guide is not greater than the diameter of the generated circumference of the upper ends of said blades.

11. A lead sharpener as set forth in claim 7 each blade terminating at its lower end adjacent a horizontal shelf that is integral with said blade.

12. A lead sharpener as set forth in claim 7 the lower inner vertical portions of said blades below said cutting edges having engaging faces, the sum of the included angles between the said faces of all of the blades equaling 360°.

13. A lead sharpener as set forth in claim 7, each of said blades including a portion extending below the apex of said pyramidal space, each portion having two vertical beveled edges with each beveled edge of one portion in engagement with the adjacent corresponding beveled edge of the next portion, the junction of said beveled edges of each portion being flattened thereby to provide a vertical opening between said portions.

14. A lead sharpener comprising a motor, a vertical shaft driven by said motor, a rotatable cutting head mounted on the upper end of said shaft, said cutting head including a plurality of blades at least one of which has a straight cutting edge, said blades fixed with respect to each other and to said shaft and spaced apart sufficiently to permit lead particles ground from said lead to be thrown by centrifugal force laterally of said blades, a lead powder receptacle above said motor and surrounding said cutting head for receiving said lead particles, a lead guide mounted independently of said receptacle and fixed with respect to said cutting head and rotatable therewith whereby a lead to be sharpened may be directed properly to said blades.

15. For use in a lead sharpener, a cutting blade having an upper sloping portion including a cutting edge, a portion below said cutting edge with vertical bevelled edges, the junction of said bevelled edges being flattened thereby to provide a vertical opening between a plurality of said blades when said blades are in engagement along their vertical bevelled edges.

16. For use in a lead sharpener, a cutting blade having an upper sloping portion including a cutting edge, a portion below said cutting edge with vertical bevelled edges

and a shelf-like structure extending away from the lower end of said cutting edge to act as a lead stop.
